UNITED STATES PATENT OFFICE.

BAGSTER ROADS SEABROOK, OF WINNIPEG, MANITOBA, CANADA.

HORN FOR TALKING MACHINES.

Application filed September 26, 1918. Serial No. 255,799.

The invention relates to improvements in horns for talking machines, particularly amplifying horns, and the general object of the invention is to provide an improved type 5 of horn which will receive sound waves and deliver the sound in a full, clear, pure and natural manner and without muffling or choking the same.

A further object of the invention is to 10 provide a horn having a reinforced neck and the flaring end thereof gradually tapering in thickness from the neck to the delivery end and to make the horn from a specially treated body of paper-like porous material 15 having one or more layers of cementitious composition, that is self-setting and becomes non-vibrant when it has set, to form the body of the horn;

A further object of the invention is to 20 construct a horn having a specially shaped neck of extra thickness also formed of non-resonant composition similar to the horn body of which it forms a homogeneus gradually thickening continuation. The disclosure 25 herein constitutes a further development of the subject matter of Serial Number 240,475 filed June 17, 1918.

With these and other objects in view, I illustrate in the accompanying drawings such 30 instances of adaptation as disclose the broad underlying features of the invention without limiting myself to the specific exemplifying details shown thereon and described herein.

With the above more important objects in 35 view the invention consists essentially in the arrangement and construction of parts hereinafter more particularly described and later pointed out in the appended claims, reference being had to the accompanying drawings in which:—

Fig. 1 represents a side view of the complete horn with portions broken away to expose construction.

Fig. 2 represents a plan view of the horn.

Fig. 3 represents an end view thereof.

Fig. 4 represents an enlarged detailed longitudinal sectional view centrally through the horn.

Fig. 5 represents a horizontal cross sectional view through the neck of the horn, the section being taken in the plane denoted by the line X—X' Fig. 4.

Fig. 6 represents a horizontal cross sectional view through the neck of the horn,

the section being taken in the plane denoted by the line Y—Y' Fig. 4.

Fig. 7 represents a horizontal cross sectional view through the neck of the horn, the section being taken in the plane denoted by the line Z—Z' Fig. 4.

Fig. 8 represents an enlarged detailed sectional view through the horn, the section showing the successive layers or courses at the point where what might be termed the 65 first reinforcement starts.

Fig. 9 represents an enlarged detailed sectional view through the horn, the section showing the successive layers or courses at the point where what might be termed the 70 second reinforcement starts.

In the drawings like characters of reference indicate corresponding parts in the several figures.

The horn indicated generally by the reference numeral 1 comprises what might be termed a flaring body part 2 and a neck 3 continuous with the body part and positioned more or less at right angles thereto. 75 4 represents the entry end of the horn and 80 5 the delivery end. The neck embodies an elbow like part 6 which elbow, for the purposes of this description, is considered as that part of the neck appearing between the lines X—X' and Z—Z' and is actually the 85 connecting part between the vertically disposed portion of the neck and the horizontally disposed inner end of the horn body. The vertically disposed part of the neck, that is to say that part extending from the 90 entrance end 4 to the line X—X', has the interior thereof circular in cross section and at the point where the elbow connects with the horn body the interior cross section is elliptical. Between the one end of the elbow 95 and the other, that is to say between the circular end and the elliptical end, the elbow gradually merges from a circular shape into an elliptical shape and gradually increases 100 interiorly in cross sectional area.

In constructing the horn, that part of the neck appearing above the line X—X' is formed with a comparatively thick wall, being considerably thicker at the front than at the back as indicated at 7 and 8 (see Fig. 5) 105 and have the side walls gradually decreasing in thickness in passing from the front to the back.

In the location indicated by the line Y—Y' the elbow is somewhat diminished in 110

thickness at the front but maintains the same thickness at the back as indicated at 9 and 10 and has the sides gradually increasing in thickness in passing from the front to the back (see Fig. 6).

Between the locations indicated by the lines X—X' and Y—Y' the thickness of the horn gradually changes in a regular manner from the section shown in Fig. 5 to that shown in Fig. 6.

Between the locations indicated by the lines Y—Y' and Z—Z' the neck gradually decreases in thickness in a regular manner from the section as shown in Fig. 6 to that shown in Fig. 7.

From the inner end of the elbow, that is to say from the location indicated by the line Z—Z', the body of the horn gradually decreases in thickness, being smallest at the delivery end 5 of the horn and it gradually flares from a comparatively small elliptical shape into a large one at the delivery end.

The horn is constructed in a special way, being made from a shell of paper like material such as papier-mâché specially treated as shortly described and afterwards coated with successive layers or courses of material built up to give the required shape to the horn as herein before described in detail.

In making the horn I first shape the paper like shell 11 and then impregnate it with a self-setting liquid solution which permeates the shell, filling the pores and which, upon setting, stiffens the shell. This part of the construction is indicated by dots applied in the sectional views in the drawings. After the liquid solution has set the horn is given a coating, both inside and out, of shellac as indicated at 12. Upon this hardening the horn is then completely enshrouded with a fabric covering indicated at 13 which fabric, such as linen, is wetted by a glue like material and is then pulled tightly around the horn, both neck and body, the edges being lapped.

Owing to the fact that the fabric is wet it in dragging, shrinks with the result that after the glue like material and fabric are dry the fabric is most tightly drawn around the horn. I next apply, both inside and out, a coating of specially selected non-shrinkable and very adhesive cement as indicated at 14, this coating being applied somewhat thicker at the neck than elsewhere. Upon this hardening I then enshroud the neck and say about two-thirds of the body of the horn next the neck with a further fabric covering 15 which is applied on the horn in the same manner as the first fabric covering.

Over this I place a further coating of cement 16, the cement coating being again made thicker at the neck than elsewhere. Upon the cement hardening I again enshroud the neck and the inner end of the horn body in a further fabric covering 17

and coat this with cement 18, the cement being again applied thicker at the neck than elsewhere. The horn as then completed is given, both inside and out, a coating of shellac 19 and upon this hardening I finish both inside and out with a final coating of varnish indicated at 20.

By applying the various courses of fabric and cement in the manner above described I am able to gradually build up the horn so that it gradually diminished in thickness from the elbow outwardly to the delivery end and such that the neck and entrance end of the horn present the form as shown in the various cross sections in the drawings and as herein before more fully described.

Whilst I have shown and described three courses of fabric and cement around the paper body or shell, still I wish it to be understood that I do not wish to be limited to this precise construction as these could be increased or diminished, depending on the size of horn which was being built.

In connection with the gradually diminishing thickness of the horn from the neck to the delivery end, I may state that this is made possible by applying the successive courses of cement so that they graduate in passing to the delivery end of the horn.

A horn made in the above manner is particularly desirable for the use for which it is designed as it is particularly light, strong, durable and inexpensive and I have found in constructing it in the particular manner shown that it is especially effective in carrying the sound waves and delivering them in a manner such that when used on a talking machine the production is full, clear and natural.

The characteristics of horns formed of a hardened cement-like composition which gradually increase in thickness from the large end to the small end are not of themselves vibrant, because the inertia of such a mass and the nature of the composition makes them quite unresponsive within the range of the sound vibrations that enter amplifying horns from any source whatever. An amplifying horn made of a non-responsive cement-like composition does not change the form of passing waves since the inertia of the heavy composition shaped into a varying thickness wall is such that it cannot set up interferences. Should an amplifying horn be responsive in the sense of setting up sympathetic waves, these would be superposed on the passing sound waves and thus change them and detract from their purity.

It is understood that the use of my invention is not limited to phonographs but it is adaptable to any and all forms of sound amplification, whether the source is mechanical, acoustical or electrical etc.

What I claim as my invention is:—

1. An amplifying horn having the body
